UNITED STATES PATENT OFFICE.

CLEMENT VACHER, OF KELOWNA, BRITISH COLUMBIA, CANADA.

NOZZLE.

964,945.

Specification of Letters Patent. Patented July 19, 1910.

Application filed April 19, 1909. Serial No. 490,883.

To all whom it may concern:

Be it known that I, CLÉMENT VACHER, a subject of the King of Great Britain, residing at Kelowna, county of Yale, in the 5 Province of British Columbia, Canada, have invented certain new and useful Improvements in Nozzles; and I do hereby declare that the following is a full, clear, and exact description of the invention, such as will 10 enable others skilled in the art to which it appertains to make and use the same.

The invention to be hereinafter described relates to nozzles.

G. Buelma of Santa Barbara, California, 15 has patented a similar nozzle in which the flow of water and the distribution are not easily controllable.

The object of this invention is to overcome these difficulties and produce a nozzle 20 which is adjustable so as to readily control both the rate of flow and the distribution of the jet or spray.

In order to more clearly disclose the construction, operation and use of the invention, reference should be had to the accompanying drawings forming part of the present application.

Throughout the several views of the drawings, like reference characters designate the 30 same parts.

In the drawings: Figure 1 is a front view of the outer shell of the nozzle; Fig. 2 is a front view of the inner shell of the same; Fig. 3 is a plan view showing the shape of 35 the delivery opening through the outer shell; Fig. 4 is a similar view showing the delivery opening through the inner shell; Fig. 5 is a longitudinal section on line 5—5 of Fig. 6; Fig. 6 is a plan view of the complete nozzle, showing the parts assembled; and, Fig. 40 7 is a side elevation of the entire apparatus, as used.

Referring to the drawings in detail, 3 represents a tubular inner shell provided with 45 a longitudinally extending triangular opening 4. The outer or front end of this shell is closed, except where the opening 4 extends radially into it. The extension 4' of the opening 4 reaches to about the center of the 50 end of the shell 3, and has a uniform width about equal to the widest part of the opening 4. Outside of this shell 3 is revolvably mounted a second tubular shell 1, provided with a triangular opening 2, 2' generally 55 similar to that of the first shell and adapted to be brought partly into register therewith.

One of the long sides of the opening 2 is parallel with the longitudinal axis of the shell 1. The opposite side of the opening is parallel with one edge of the opening 4. In 60 order to regulate the jet or stream passing through the opening 2, it is simply necessary to turn the outer shell slightly to make the openings 2 and 4 register more or less exactly. The entire flow may be quickly and 65 easily cut off by simply turning the outer shell so that its opening does not in any degree register with the opening 4.

When the two shells are in the position shown in Fig. 6, there will be a broad fan-like spray, as shown at the left in Fig. 7, the jet being under low pressure. The straight edge of the shell 1, of course, begins to overlap the opening 4 at the widest part of the opening, first. It will overlap practically one-half of the opening 4 before it acts upon the full length of the opening. It will be noticed, however, that the branches 75 4' and 2' of the openings 4 and 2 are radial and extend from the centers of the ends of the shells to their outer edges, and that these branches are of practically the same width throughout. Consequently, as the outer shell 80 is rotated, the overlapping of the adjacent edge of the radial opening 4' by the outer 85 shell will increase much more rapidly toward the outer end of the opening than at the opposite end. As a result of this construction, it is possible to completely close the longitudinal opening through the inner 90 shell, while at the same time leaving the inner end of the radial branch 4' uncovered. The vertical jet is delivered through the opening 4 and the horizontal jet through the opening 4'. Therefore, by rotation of the 95 outer shell, it is possible to either reduce both jets simultaneously, or, by further turning of the shell, to completely cut off the vertical jet and at the same time reduce the horizontal jet from a wide spray-like stream to a 100 simple non-spraying jet. To effect locking of this outer shell, a thumb screw 5 is provided. The shank of this screw is adapted to play in an arcuate slot in the outer shell 1, and its lower end takes into the wall of the inner shell. Its head is provided with a shoulder which engages the face of the outer shell when it is turned down, and so locks the two shells together frictionally, preventing relative movement between them. 105

The particular formation of the openings 2 and 4 gives the jet or escaping spray both 110

a forward and a side motion, thus distributing the liquid from the nozzle to greatest distance to which the nozzle will project.

This nozzle may have a variety of uses 5 as in sprinkling streets, lawns, and gardens and for fire protection. It is designed especially for use in irrigation work for irrigating large areas. For this purpose two nozzles may be mounted on opposite ends 10 of a cross head 14 (Fig. 7) of a rotary spray mechanism 15. The ends of the cross head pipes are slightly bent and the nozzles turned through a slight vertical angle so as to cause the cross head to revolve by the 15 reaction of the escaping jet or spray. As the cross head rotates the ground from the center of rotation to the greatest distance to which the nozzle will project is sprinkled and the proper distribution is effected by 20 adjusting the forward and side flow of the adjustable nozzles so as to get the desired results. The chief objection to this nozzle for this purpose is that it will not project to a great distance, therefore better results 25 will be secured if on one end of the cross head 14 another form of nozzle be substituted which will project to a greater distance covering, as the cross head 14 revolves, an annular space beyond the reach of the 30 nozzle here described.

Having thus fully described my invention, what I claim as new and useful, and desire to secure by Letters Patent, is:—

1. A nozzle of the character described 35 comprising an inner tubular shell having one closed end and provided with a longitudinally extending triangular delivery opening and a radially extending branch opening leading therefrom through the

closed end of the shell, and an outer shell 40 revolvably mounted on said inner shell and provided with openings adapted to coöperate with the openings in the inner shell.

2. A nozzle of the character described 45 comprising an inner tubular shell having one closed end and provided with a longitudinally extending triangular delivery opening and a radially extending branch opening leading therefrom through the closed end of the shell, an outer shell revolvably mounted on 50 said inner shell and provided with openings adapted to coöperate with the openings in the inner shell, and means for locking said outer shell in various adjusted positions.

3. A nozzle of the character described 55 comprising an inner tubular shell having one closed end and provided with a longitudinally extending triangular delivery opening and a radially extending branch opening leading therefrom through the 60 closed end of the shell, and an outer shell revolvably mounted on said inner shell and provided with coöperating openings, the walls of which are so disposed as to simultaneously reduce both openings of the inner shell, upon partial rotation of the outer shell, or, upon continued rotation to completely close the longitudinal opening of the inner shell while only reducing the radial opening therethrough, or, upon further continued rotation, to completely close both 65 openings through the inner shell.

In witness whereof I have hereunto set my hand in the presence of two witnesses.

CLÉMENT VACHER.
